UNITED STATES PATENT OFFICE.

WALTER WESTRUP, OF WAPPING, ENGLAND.

GRAIN-MILL.

Specification of Letters Patent No. 11,011, dated June 6, 1854.

To all whom it may concern:

Be it known that I, WALTER WESTRUP, of Wapping, in the county of Middlesex, England, miller and biscuit baker, a subject 5 of the Queen of Great Britain, have invented or discovered new and useful Improvements in Grinding Corn or Grain; and I, the said WALTER WESTRUP, do hereby declare that the nature of the said invention and in what manner the same is to 10 be performed are fully described and ascertained in and by the following statement thereof, reference being had to the drawings hereunto annexed and to the figures and 15 letters marked thereon—that is to say:

My improvements in machinery for grinding corn or grain consist in making the running stones with conical grinding surfaces in place of flat ones as is usually 20 the case. In this improved arrangement the bottom stones are the runners, the upper stones being stationary and made in the form of a ring with inclined inner surfaces, so as to fit and as it were to surround the 25 bottom stones or runners. The runners of both pair of grinding stones are mounted one above the other on the same vertical shaft and are arranged in such a manner that the first pairs will break down the corn 30 or grain and partially pulverize it. The meal then passes from the first pair of stones into a kind of short dressing machine, where the fine flour is separated from the under-ground meal, which passes between the sec- 35 ond pair of stones, where it is completely ground. By this means the corn is passed through the mill in much less time than usual and thereby an increased amount of work in a given time is effected. The 40 grinding surfaces being conical, also facilitate the delivery of the flour therefrom and thus prevent it from being spoiled or damaged by heating from friction.

The improved arrangement of apparatus 45 for grinding corn or grain is shown in the drawings hereunto annexed.

Figure 1 is a vertical section taken through the middle of the machine; Fig. 2, a plan or partial sectional view taken in the line 50 1, 2, of Fig. 1, and Fig. 3 a sectional plan view of the machine taken in the line 3, 4, of Fig. 1.

In this arrangement two pairs of stones are employed. The lower stones E, E, are 55 the runners and are fixed one above the other on a hollow vertical shaft F, which

turns in bearings made in the frame-work. The grinding surface of the stones E, is conical or inclined and lateral holes are made in the stones from the eye to the 60 grinding surface (as shown at Fig. 1 and also in the sectional plan view, Fig. 4) for the purpose of admitting air to the grinding surface in order to keep it cool. To facilitate this operation the driving shaft 65 F, is made hollow and is supplied with air by a pipe from above, the air being admitted to the eye of the stone by means of lateral holes communicating with the interior of the shaft. The top stones G, G, are sta- 70 tionary and are of an annular shape, their grinding surfaces being inclined to correspond with the conical surface of the runner or bottom stone. For the convenience of adjustment the upper stones are mounted in annular frames S, S, which are by means of projecting pieces 1, 1, 1, (see Figs. 2, 3, and 5) supported upon a stationary ledge 2, 2, 2, which is secured to the fram- 75 ing. The mode of mounting and adjust- 80 ing the top stone will be best understood by referring to the detached view, Fig. 5, which represents in elevation the parts in immediate connection with the stones. It will be seen upon referring to this figure 85 that the parts of the ledge 2, 2, 2, upon which the projecting pieces 1, 1, 1, of the annular frames S, S, rest, are inclined, so that by merely turning the frame S, S, slightly around horizontally the stone may 90 be adjusted to the surface of the runner with the greatest nicety. In order to effect this adjustment a small toothed rack t, is made on the outside or periphery of the annular frame S, S, and this rack gears 95 into an endless screw u on one end of which is mounted a bevel pinion or miter-wheel. This wheel is driven by a similar pinion on the upper end of a vertical shaft v, which is actuated by means of a similar pair of 100 miter-wheels and the hand-wheel w. The operation, mode of mounting, and adjust- 105 ment of the lower pair of stones is precisely similar to the upper, and therefore no sepa- rate description is required.

The apparatus is fed with corn to be ground by the pipe H, and the feed is regulated by a sliding pipe or tube x, which in- 110 closes the bottom of the feed pipe and may be moved up and down by a lever y, the op- posite extremity of which is jointed to a long rod z, threaded at its lower end and

furnished with a hand-wheel and thumb-screw, whereby the rod α may be raised or lowered and the feed regulated at pleasure by bringing the lower edge of the sliding 5 tube α nearer to or farther from the circular plate 3, in the feed box. The amount of feed having been properly adjusted by the means just described, the corn will pass down the pipe α , into the feed box, and from 10 thence down the pipe 4, into the box 5, immediately above the eye of the upper stone. From this box 5 the corn will pass between the grinding surfaces of the stones G, and E, and will be broken down and partially 15 pulverized. The meal will quickly find its way out from between the stones and will fall down on to the conical inclined surface 6, 6, from whence it will pass into a wire cylinder I, I, in which a number of 20 brushes 7, 7, similar to those of a dressing machine work. These brushes 7, 7, are mounted on the main shaft F, and rotate with it, and as the meal falls into the cylinder they will brush the already pulverized 25 flour through the fine meshes of the wire and allow it to fall down the inclined surface 8, 8, into a chamber J below (shown best at Fig. 5), while the partially ground meal will fall down the inclined surface 30 9, 9, and pass between the second pair of stones (as shown at Fig. 1). By this second operation the meal will have become completely ground or "softened down," and when it escapes from the second pair of 35 stones it will fall into the chamber J, into which the flour from the previous grinding operation has already fallen. It will be understood that the object of separating the flour from the meal after the first grinding 40 operation is that the flour already produced may not be allowed uselessly to pass through the second pair of stones.

At the bottom of the chamber J, is a table K, which is mounted on the vertical driv-

ing shaft and receives a rotary motion there- 45 from. The meal as it falls on to this revolving table K, is by the rotation of the latter brought against the arm 10, (see Figs. 5 and 6,) which sweeps it into the spout 11, from whence it falls into a bin or receptacle 50 below. To the under side of the revolving table K, are attached a number of sweeps or curved arms (shown by dots at Fig. 6), whereby any meal that may get under the table is swept out into the spout 11, as the 55 table K rotates.

It is almost unnecessary to state that the principal working parts are inclosed by a casing N, made of canvas or other suitable material, for the purpose of preventing the 60 flour from being blown about.

Motion is communicated to the working parts by means of the bevel gearing shown at L, L, Fig. 1, which is actuated by any prime mover.

What I claim as my invention and desire to secure by Letters Patent of the United States is—

The general arrangement and combination of parts herein described—that is to 70 say, the use of two or more pairs of mill stones, the runner of each pair being mounted on the same vertical shaft, and arranged in such manner that when the meal escapes from the first pair of stones it may be subjected to a dressing operation, for the purpose of separating the already formed flour from the unground meal, as set forth, leaving the unground meal, when freed from the flour, to pass through the second pair of 75 80 stones to perfect the grinding operation, substantially in the manner as herein described.

WALTER WESTRUP.
